GOLF CLUB

Milton B. Reach, Springfield, Mass.

Application October 17, 1944, Serial No. 559,027

5 Claims. (Cl. 273—80)

1

The present invention relates to golf clubs and more particularly pertains to improvements in the shafts of golf clubs so as to obtain better control of the club head as it approaches the ball.

An object of the invention is to provide accuracy in the use of the club without undesired stiffness of the shaft, and to minimize errors that occur from a faulty face contact of the club head with the ball wherein the shaft is designed to prevent severe flexing adjacent the head of the club and thereby provide that the head of the club more accurately engages the ball upon impact therewith.

Another object of the invention resides in stiffening the shaft in the vicinity of the club head so as to provide less relative movement of the club head with respect to the portion of the shaft adjacent the club head and thereby provide for less mobility of the club head as the club head approaches the ball and during impact therewith.

Other objects and features of the invention will be more apparent as the present disclosure proceeds and upon consideration of the accompanying drawings and the following detailed description wherein an exemplary embodiment of the invention is disclosed.

In the drawings:

Fig. 1 is a diagrammatic view illustrating the manner in which a golf club shaft of an ordinary type is distorted during the early stages of a swing.

Fig. 2 is a similar view showing the manner in which the shaft of a conventional club is distorted as the club head approaches the ball to dislocate the club head with respect to the ball.

Fig. 3 is a diagrammatic view illustrating a golf club constructed in accordance with the present invention wherein the shaft is immobilized in the area adjacent the head of the club.

Fig. 4 is a perspective view of a golf club shaft embodying the present invention.

Fig. 5 is a side elevational view partly in section of that portion of the shaft indicated at 5 in Fig. 4.

Fig. 6 is a side elevational view of that portion of the shaft designated at 6 in Fig. 4.

Fig. 7 is a fragmentary side elevational view of the portion of the shaft shown at 7 in Fig. 4.

Fig. 8 is an elevational view of the hosel or stem of the club head and showing the lower end of the shaft in section.

Fig. 9 is a sectional view of the connection between the hosel and the shaft, and taken on the line 9—9 of Fig. 8.

2

Fig. 10 is a transverse sectional view of a portion of the hosel.

The present invention is directed to the shafts of golf clubs which are designed to reduce the flexibility of the shaft in the vicinity of the club head, and to thereby stabilize the club head during swing of the club as the club head moves into engagement with the ball. In the manufacture of golf clubs, great care has been exercised in shaping the face of club heads, and particularly golf clubs of the iron type. It has been a practice to provide what is known as registered sets of iron clubs wherein tedious efforts are employed to provide uniform increments of loft in a set of clubs. The average golf club shaft measures approximately one-half an inch in diameter at the handle end thereof. The diameter of a conventional golf club shaft tapers downwardly from the handle portion to a diameter of approximately five-sixteenths of an inch at the lower or hosel end. The swinging of a club provided with such a shaft produces a distinct curvature in the head area of the shaft, and particularly in the hands of a hard hitter or an expert golfer. This curvature or flexible characteristic of the shaft accentuates the problem of timing as well as the maintenance of the face of the club head in proper relation to the ball as the club moves into contact with the ball.

The average golf club shaft bends backwardly as the down swing is started, and this bending of the club is clearly evident from consideration of stroboscopic pictures depicting a full swing with a conventional club. This phenomena appears to result from the fact that the center of gravity of the mass of the combined club head and shaft is located in the vicinity of the club head, and as the swing starts the mass tends to bend the club shaft backwardly as shown in Fig. 1 of the accompanying drawings at least until the inertia of the club head is overcome. A proper golf club stroke includes the uncocking or snapping of the wrists prior to hitting the ball and at a point in the swing between the club positions shown in Figs. 1 and 2. As the wrists are uncocked the movement of the club head is accelerated, the head portion of the club snaps forwardly, and the club head is thus in advance of the axis of the shaft, as shown in Fig. 2. This forward movement of the club head following the uncocking of the wrists tends to dislocate the club head and the face thereof with respect to the ball. The dislocation of the club face from a position at right angles to the direction of the ball path by as

much as one degree will affect the flight of the

golf ball by as much as ten yards in a two hundred and twenty-five yard drive. Thus, if the mobility of the head area throws the nose of the club in faster than the heel portion, a pronounced hook results. The mobility of the club also results in the loft being changed and the expected or anticipated distance resultant from the choice of a particular club is upset. The golf club shaft should be so constructed as to provide for some mobility of the club head, and this is desirable for providing a cushioning effect under impact, but expert golfers who have contributed such low scoring records have had to forego the pleasing attribute of cushioning in favor of stiffness of the shaft so as to obtain the necessary accuracy.

Moreover if the mobility of the club head is great it is easily deflected from its initial impact angle during the flattening of the ball by the club face. Under this circumstance, if the torsional energy thus stored in the shaft is concentrated so that the shaft quickly unwinds and swings the club head back to or beyond its initial impact angle during the expansion of the ball before it leaves the club face, a tendency to hook or slice is apt to be imparted to the ball by the mobility of the club head during the impact therewith.

The present invention provides for a reduction in the mobility of the club head area without depriving the shaft of the flexibility necessary for nice feel or proper control of the flight of the ball. It will be observed that the shaft is distorted in Fig. 2 as the club head is about to engage the ball, and it is an object of the present invention to provide a golf club shaft with such characteristics that the club head moves into engagement with the ball without relative displacement of the club head from the axis of the adjacent portion of the shaft to thereby obtain the intended direction of flight of the ball and the intended loft for the particular club that is being used.

These objects are obtained in general by stiffening that portion of the shaft adjacent the hosel or the club head and shifting the greatest point of flexibility upwardly along the shaft to a position more intermediate the ends of the shaft. In an exemplary embodiment the area of the greatest flexibility of the shaft is not less than six inches from the sole of the club head. The shaft starting from each end has approximately equal diameters, and the diameter of the shaft is progressively reduced proceeding from each end, meeting in a relatively small diameter waist section.

Referring now to the drawings, there is shown at 10 a golf club head which for the purpose of illustration is shown as being of the iron type. The connection between the club head and a shaft exhibiting the present invention may be of any type, and in the embodiment illustrated this union is provided by means of an internal hosel connection. The hosel 11 is accordingly reduced in diameter to provide a shoulder 13 and a stem 12 of a smaller diameter than the hosel 11. The diameter of the stem 12 is preferably such that when the lower end 22 of a hollow metallic shaft is arranged thereon the diameter of the lower end portion of the shaft will be substantially equal to the portion 11 of the hosel. This arrangement provides for a symmetrical joint between the hosel and the shaft.

The stem 12 is provided with longitudinally extending grooves 14 which may be arranged at diametrically opposite points, as shown in Fig.

10. The inner surface of the lower end portion 22 of the hollow shaft is provided with inwardly projecting lugs 16 which are adapted to engage the stem 12 within the grooves 14 as the hosel 5 is introduced into the hollow shaft. The lugs 16 may be formed by indenting the shaft around openings for a retaining pin or rivet 17 which extends through the stem 12 and the shaft. The pin or rivet 17 may be swaged at the ends to 10 provide substantially flat rivet heads which are seated within the depressions which form the inwardly projecting lugs 16. The rivet heads are thus flush with the peripheral surface of the shaft. The lugs or depressed rivet seats 16 engage the stem 12 within the grooves 14 and accordingly remove any shearing strains from the rivet 17. The depressed lugs 16 also provide indentations for receiving the heads of the rivets 17 and thus provide a symmetrical appearance for the exterior of a union between the shaft and the hosel.

The general organization of the shaft is illustrated in Fig. 4 and it will be observed from a consideration thereof that the lower end portion 22 of the shaft is of a diameter corresponding substantially to that of the hosel 11, and in an exemplary embodiment of the invention the diameter of the portion 22 of the shaft is approximately one-half inch. The shaft is provided with a handle portion 23 having a suitable hand grip covering thereon. The shaft providing the handle, and particularly the portion 24 may also be approximately of one-half inch in diameter, and therefore corresponds substantially to the diameter of the lower end portion 22. The shaft in proceeding from each of the end portions 22 and 24 is progressively reduced in diameter to provide a waist section 26 which is spaced from the sole of the club by a distance not less than six inches from the sole of the club.

The shaft may be formed of tubular metal having a gauge of about .030 inch, and the shaft in proceeding upwardly from the lower end portion 22 may be reduced in diameter in five reduction steps of approximately .075 inch each. The outside diameter of the portion 27 of the shaft may therefore be about three-eighths of an inch. The portion 27 of the shaft terminates at the point indicated at 28 and another portion 29 of the shaft fits within the section 27, as shown in Fig. 5. The section 27 thus telescopes over the section 29, and these two portions of the shaft may be joined in any suitable manner, such as by a welding or soldering operation. The length 55 of the waist section 26 may therefore be adjusted prior to the welding operation by varying the position of the section 29 within the section 27.

The length of the waist section 26 may be further adjusted by altering the length of sections 31 and 32. The length of the waist section 26 may vary between one and one-half inches and six inches, depending upon the type of club on which the shaft is used. In a niblick type club the waist section 26 of the shaft may be shorter than in a mid-iron or driving iron shaft.

The shaft increases in diameter from the section 29 to the section 24, and this increase in the shaft diameter may be accomplished by means of a plurality of sections which are progressively of larger diameter. The section 33 of the club may have an outside diameter of approximately seven-sixteenths of an inch and extend throughout a length of approximately two and one-half inches and then enlarge to the

diameter of the section 24 adjacent the handle of the club.

The golf club shaft thus provides a structure wherein the walls of the shaft are of a diameter to provide an area adjacent the hosel substantially equal to the diameter of the hosel and extending upwardly for a distance at least equaling the length of the hosel member, and thereafter reduced to its minimum diameter by a taper so gradual as to produce a relatively stiff area for a distance of not less than six inches from the sole of the club head 10. This relatively stiff portion of the shaft prevents pronounced bending of the shaft in the area adjacent the club head and thereby stabilizes the club head during the swinging of the club, and particularly as the club head moves into engagement with the ball. Thus when the wrists are snapped and the club head is accelerated in approaching the ball, the face of the club head does not become dislocated and is maintained in a position to impart the desired trajectory to the ball as it leaves the face of the club head. Moreover, since the torsional inertia of the club head is somewhat augmented by the stiffening of the adjacent portion of the shaft, the tendency of the club head to deflect and restore during the interval of impact is reduced. In addition as the torsional stress applied through the stiffened section to the waist section finds there a section of minimum diameter and greatest flexibility of considerable axial extent, the torsional stress does not concentrate at any part of that section, but spreads progressively therein. This renders the tendency of the shaft to unwind from its torqued condition somewhat "lazy." The added torsional inertia and lazy action of the distributed torque storage, in cooperation with each other, tend to reduce the degree of club head deflection and retard the speed at which the club head swings back toward its angle of initial impact after deflection, and thus tend to minimize any tendency thereof to contribute in imparting hook or slice to the ball.

While the invention has been described with reference to specific structural details of the connection between the shaft and the club head and with regard to a shaft of a particular type, it will be appreciated that changes may be made in all of the features. Such modifications may be made without departing from the spirit and scope of the invention as set forth in the appended claims.

I claim:

1. A tubular steel golf club shaft having an elongated cylindrical waist zone of uniform wall thickness, and of minimum diameter and maximum flexibility relative to the balance of the shaft, the shaft progressively increasing in diameter from one end of said zone to its head-end be a series of cylindrical sections, that of largest diameter being of a size enabling it, in a club assembly, to telescope over the hosel of a club head, and the shaft further including a portion forming a continuation of the opposite end of the waist zone including a plurality of cylindrical sections of progressively increasing diameters, the end section being of a size and length to constitute a foundation for a grip element.

2. A tubular steel golf club shaft progressively tapering from its grip and head ends by a series of stepped cylindrical sections of decreasing diameter to the opposite ends of an elongated

5 cylindrical waist section, said waist section in respect to the balance of the shaft being of minimum diameter and maximum flexibility, the head end of the tubular shaft being cylindrical and of a size enabling it, in a club assembly, to telescope 10 on the hosel of a club head, and the grip end of the tubular shaft being non-stepped throughout a distance at least substantially equal in length to that of a grip element.

3. A shaft as recited in claim 2 in which the 15 zone of relatively minimum diameter and maximum flexibility is spaced so that in a club assembly it lies not less than six inches from the club head sole.

4. A tubular steel golf club shaft having an elongated cylindrical section of minimum diameter relative to the balance of the shaft and of uniform wall thickness and constituting an elongated waist section of maximum flexibility relative to the balance of the shaft, said shaft 20 having a head section of elongated cylindrical form, larger than that of said waist section and of a size enabling it, in a club assembly, to telescope on the hosel of a club head, said head section being connected to the adjacent end of 25 said waist section by a third section, made up of a plurality of stepped cylindrical portions, and said tubular shaft having a fourth section of increasing diameter extending from the opposite end of the uniform diameter waist section and 30 further having therebeyond a grip section at least equal in diameter to the maximum diameter of said fourth section and of a length at least substantially equal to the length of a golf club grip.

5. A tubular steel golf club shaft having head 40 and grip sections of maximum diameter and of elongated substantially cylindrical form, said shaft having a waist section of materially smaller diameter than said head and grip sections and of elongated cylindrical form, said head section 45 being connected to one end of said elongated cylindrical waist section by a section comprising a series of stepped cylindrical portions of decreasing diameter, and said grip section being connected to the other end of said elongated cylindrical waist section by another section of progressively decreasing diameter.
